ADJUSTABLE EXTENSION BROILER

Filed Oct. 15, 1934

FIG. 2.

UNITED STATES PATENT OFFICE

2,008,222

ADJUSTABLE EXTENSION BROILER

Edward W. Pape, St. Louis, Mo.

Application October 15, 1934, Serial No. 748,341

3 Claims. (Cl. 126—41)

This invention relates generally to broilers adapted for use in association with stoves and other heat-producing means, and more specifically to an improved broiler which is so constructed and arranged that the food-supporting portion thereof is capable of being extended outwardly beyond the broiling compartment of the associated stove or other heat-producing means, and also is adjustable vertically relative to the broiling compartment burner means of said stove or other heat-producing means, the predominant object of the invention being to provide an improved broiler of the class described which, because of improved details of construction thereof, functions with much more efficiency than did other similar broilers heretofore known.

The improved broiler disclosed herein is an improvement on the adjustable extension broiler covered by United States Patent No. 1,852,087, granted to me on April 5, 1932. The features of improvement which are present in the structure disclosed herein and are not found in my previously patented broiler are the improved means for securing the elevating frame of the improved device in different elevated positions; the improved means for providing for free sliding movement of the sliding frame relative to the stationary frame of the structure; and the improved manner of insuring alined movement of the sliding frame with respect to the stationary frame.

The improved features referred to above are described in detail in the following specification, and are illustrated in the drawing, in which

Fig. 1 is a fragmentary front elevation of a stove having the improved adjustable extension broiler associated therewith.

Fig. 2 is a fragmentary vertical section taken through the broiling compartment of a stove showing the improved broiler in place therein, and illustrating by broken lines an extended and elevated position of the food-supporting portion of the broiler.

Fig. 3 is a plan view of the improved broiler, with the food-receiving pan removed.

Fig. 4 is an enlarged fragmentary sectional view illustrating the means for securing the elevating frame of the improved broiler in various elevated positions.

Fig. 5 is an enlarged fragmentary side elevation of the broiler showing the means which provide for free sliding movement of the sliding frame relative to the stationary frame.

Fig. 6 is an enlarged fragmentary section illustrating the means for insuring alined movement

of the sliding frame with respect to the stationary frame.

In the drawing, wherein is shown for the purpose of illustration, merely, one embodiment of the invention, A designates a stove which is provided with a broiling compartment B. The stove A includes a suitable door C, which acts as a closure element for the broiling compartment B as well as for an oven (not shown) located above said broiling compartment.

Arranged within the lower portion of the broiling compartment B of the stove A is my improved adjustable extension broiler D, which includes a stationary frame 1, a sliding frame 2, and an elevating frame 3. The stationary frame 1 is rectangular in shape and preferably, though not necessarily, is made up of angle bar members which are welded or otherwise secured together in their assembled form to produce the frame. The opposite side members of the stationary frame 1 are provided with pairs of inwardly extended lugs 4, and suitable fastening devices 5 are extended through apertures formed through these lugs and through openings formed in the bottom wall of the broiling compartment for the purpose of fixedly securing the stationary frame in place. The stationary frame includes also a bar 6 which extends longitudinally of said stationary frame at the approximate transverse center of the frame, and this bar 6 is provided with a slot 7 which is extended longitudinally thereof, as shown in Fig. 3.

Arranged immediately above the stationary frame 1 of the broiler structure is the sliding frame 2, which likewise is rectangular in shape and is formed of angle bar members welded or otherwise secured together in their assembled form. The angle bar members of the stationary frame 1 are arranged so that legs thereof are extended horizontally and downwardly, while the angle bar members of the sliding frame 2 are arranged so that legs thereof are extended horizontally and upwardly. The horizontal legs of the angle bar members of the frames 1 and 2 are spaced apart from each other vertically, and interposed between said horizontal legs of said frames are anti-friction devices 8. The anti-friction devices may be of any suitable type, and preferably pairs of said devices are arranged between the side angle bar members of the frames 1 and 2, as indicated by dotted lines in Fig. 3. By preference the two anti-friction devices 8 located adjacent to the forward ends of the frames 1 and 2 are secured to the stationary frame 1, while the two anti-friction devices adjacent to

the rear ends of the frames 1 and 2 are secured to the sliding frame 2 (Fig. 5). The particular type of anti-friction device illustrated in the drawing comprises a cage 8^a in which a ball 8^b is arranged for free rotary movement. The cages of the anti-friction devices are secured to one frame and the balls which extend beyond the cages contact with the other frame, and as a result of this arrangement the sliding frame 2 moves freely with respect to the stationary frame 1.

The sliding frame 2 is provided with a bar 9 which extends longitudinally of said frame in vertically aligned parallelism relative to the bar 6 of the stationary frame 1. The bar 9 is provided with a pair of apertures through which bolts or like elements 10 pass, these bolts passing also through the slot 7 formed in the bar 6 of the stationary frame 1. The bolts 10 are provided with heads and nuts, and said nuts are positioned on the bolts so that said bolts are loose relative to the bars 6 and 9. Thus when the sliding frame 2 is moved forwardly or rearwardly of the stationary frame 1, the bolts 10 move longitudinally of the slot 7 in the bar 6, whereby the sliding frame 2 is guided in its movement with respect to the stationary frame. As an additional means for guiding the movement of the sliding frame 2, I provide a yoke 11 (Figs. 2 and 6) which is secured by welding or otherwise to the bar 6 of the stationary frame and embraces the bar 9 of the sliding frame. During movement of the sliding frame 2 the bar 9 thereof moves through the yoke 11 to insure aligned movement of the sliding frame. In addition to performing the function of guiding the movement of the sliding frame 2, the bolts 10 and yoke 11 prevent upward movement of the sliding frame with respect to the stationary frame.

The elevating frame 3 is rectangular in shape and is formed of angle bar members which are welded or otherwise secured together in their assembled form. The elevating frame is of approximately the same width as the stationary and sliding frames, but is of less length than the latter frames, as shown most clearly in Figs. 2 and 3 of the drawing. The angle bar members of the elevating frame 3 are arranged so as to provide horizontally and vertically disposed leg portions, the horizontally disposed leg portions being at the top of the frame. In order to movably secure the elevating frame 3 to the sliding frame 2, I employ arms 12, four of such arms being illustrated with a pair thereof at each side of the associated frames 2 and 3. Each arm 12 is pivotally secured to a longitudinally extended side angle bar member of the sliding frame 2 and to an adjacently arranged, longitudinally extended side angle bar member of the elevating frame 3. The arms are mounted so as to be continually in a state of parallelism, and with the arms located opposite each other disposed in the same plane. It will be seen, therefore, that in any position of the elevating frame 3 relative to the sliding frame 2 the planes of these two frames will be parallel, and that when the plane of the stationary frame 1 is horizontal, which is the case in practice, the sliding frame 2 and the elevating frame 3 will always be in horizontal planes. At the forward end of the elevating frame 3 a suitable handle 13 is fixed thereto to facilitate imparting sliding movement of the sliding frame and elevating movement to the elevating frame.

The means for maintaining the elevating

frame 3 in various elevated positions to which it has been moved comprises opposed racks 14, which are secured to the opposite side angle bar members of the sliding frame 2. The means referred to includes also a bar 15 which extends transversely of the elevating frame 3 at a point immediately adjacent to the forward end thereof. The bar 15 at its opposite ends is supported for rotary motion by the opposite side angle bar members of the elevating frame 3, and fixed to said bar 15 is a pair of arms 16. The arms 16 extend rearwardly of the bar 15, and the rear end portions of said arms 16 are supported by teeth of the racks 14. The bar 15 has fixed to it at its approximate center an operating member 17, which is curved downwardly and forwardly and upwardly, and is provided with a portion 17' that is disposed immediately adjacent to the handle 13 of the elevating frame 3.

It will be observed that when the sliding frame 2 has been moved to its outermost position and the elevating frame 3 has likewise been moved to its outermost position (note broken line positions of these frames on Fig. 2), said elevating frame is disposed in a position in front of the plane of the front wall of the associated stove A. The elevating frame is maintained in this forwardly projected position by the forward arms 12 contacting with stop elements 18 formed on the sliding frame 2. It will be noted also that the distance between the planes of the elevating frame and the sliding frame is varied when the arms 12 are rotated on their pivot points, and that the elevating frame may be moved from its lowermost elevation, where the elevating frame rests upon the sliding frame (the rearmost position of the elevating frame relative to the sliding frame), to its highest elevation, where the arms 12 are in vertical planes. Because of the reduced length of the elevating frame 3, said elevating frame may be adjusted to different elevations within the broiling compartment of the stove A without any portion of said elevating frame being extended beyond the front wall of the broiling compartment. It is possible therefore, to adjust the elevating frame so that the food being broiled is positioned the proper distance from the burner means B' of the broiling compartment, and to close the door C of the broiling compartment without interference from the adjusted elevating frame.

When the elevating frame is being adjusted to different elevated positions, the handle 13 is grasped and drawn upwardly and forwardly. This rotates the arms 12 on their pivots and also causes the free rearmost end portions of the arms 16 to slide over the teeth of the racks 14. When the desired elevation of the elevating frame has been reached, the handle is released and the free rearmost ends of the arms 16 will engage teeth of the racks 14 and maintain the elevating frame in the position to which it has been adjusted (Fig. 4). When it is desired to release the elevating frame from a position to which it has been adjusted, the portion 17' of the operating device 17 is depressed by moving a thumb or finger thereagainst, whereby the free rearmost end portions of the arms 16 will be elevated to disengage same from the teeth of the racks 14.

When in the use of the improved broiler it is desired to position an article to be broiled in the broiling compartment of the stove, the broiling compartment door is opened and the handle 13 is drawn outwardly to move the sliding frame to its forwardly projected position. The handle 13 is then drawn forwardly and upwardly to elevate

the elevating frame in the manner already explained. When the article has been positioned in the broiler pan D', the elevating frame is adjusted to the desired elevation, after which the 5 sliding frame and the adjusted elevating frame are moved inwardly into the broiling compartment of the stove and the door of said broiling compartment is closed.

By employing means for securing the elevating 10 frame in different positions which operate at opposite sides of the broiler, the elevating frame is evenly supported throughout. Also, the anti-friction devices 8 between the sliding frame 2 and the stationary frame 1 eliminate all binding be- 15 tween these frames and therefore render movement of the sliding frame exceptionally easy. Finally, the use of the yoke 11 insures perfectly aligned movement of the sliding frame relative to the stationary frame.

20 I claim:

1. A broiler comprising a sliding frame, means for supporting said sliding frame for sliding movement, an elevating frame, means for operatively attaching said elevating frame to said sliding frame, a handle fixed to said elevating frame for moving said sliding frame and said elevating frame slidably as a unit relative to said supporting means and for raising and lowering said elevating frame relative to said sliding frame, and 25 means for selectively maintaining said elevating frame in selected elevated positions to which it has been moved, the last mentioned means including an operating element disposed at said handle, said handle and said operating element 30 being so constructed that each may be simultaneously engaged by a single hand of a user of the broiler.

2. A broiler comprising a sliding frame, means

for supporting said sliding frame for sliding movement, an elevating frame, means for operatively attaching said elevating frame to said sliding frame, a handle fixed to said elevating frame for moving said sliding frame and said elevating frame slidably as a unit relative to said supporting means and for raising and lowering said elevating frame relative to said sliding frame, and 5 means for selectively maintaining said elevating frame in selected elevated positions to which it has been moved, the last-mentioned means including a pair of arms adapted to releasably engage parts of said sliding frame and an operating element cooperatively associated with said arms for moving same, said operating element being 10 disposed at said handle and said handle and said operating element being so constructed that each may be simultaneously engaged by a single hand of a user of the broiler.

3. A broiler comprising a sliding frame, means 20 for supporting said sliding frame for sliding movement, an elevating frame, means for operatively attaching said elevating frame to said sliding frame, a handle fixed to said elevating frame for moving said sliding frame and said elevating frame 25 slidably as a unit relative to said supporting means and for raising and lowering said elevating frame relative to said sliding frame, said handle being of substantially yoke-shaped formation, and means for selectively maintaining said 30 elevating frame in selected elevated positions to which it has been moved, the last-mentioned means including an operating element disposed with a portion thereof extended within the yoke-shaped handle whereby said handle and said 35 operating element may be simultaneously engaged by a single hand of a user of the broiler.
